UNITED STATES PATENT OFFICE.

MICHAEL VIDAK, OF CHICAGO, ILLINOIS.

FLOOR SCRUBBING AND WIPING MACHINE.

1,010,097.

Specification of Letters Patent. Patented Nov. 28, 1911.

Application filed July 24, 1911. Serial No. 640,212.

To all whom it may concern:

Be it known that I, MICHAEL VIDAK, a subject of the King of Hungary, residing at Chicago, in the county of Cook and State of Illinois, have invented certain new and useful Improvements in Floor Scrubbing and Wiping Machines, of which the following is a specification, reference being had therein to the accompanying drawing.

10 This invention relates to a floor scrubbing and wiping machine, and the primary object of my invention is to provide in a manner as hereinafter set forth a machine that can be advantageously used in large office buildings and auditoriums for scrubbing and 15 cleansing large floor spaces in a manner that is expeditious and economic.

Another object of the invention is to provide a machine of the above type having a 20 rotary scrubbing roll and a rotary wiping or absorbent roll, both of which coöperate in thoroughly cleansing a surface, and combining with the said rolls a trough, a wringer roll associating with the absorbent 25 roller, a collection receptacle, and a conduit leading from the trough to the receptacle for conducting the matter deposited in the trough by the wringer roll.

With the above and other objects in view, 30 the invention resides in the novel construction, combination and arrangement of parts to be hereinafter specifically described and then claimed.

Reference will now be had to the drawings, wherein like numerals denote corresponding parts throughout the several views, in which:

Figure 1 is a side elevation of a machine in accordance with this invention, Fig. 2 is a 40 longitudinal sectional view of the same, Fig. 3 is a plan of the machine, Fig. 4 is a perspective view of a portion of the adjustable frame of the machine, and Fig. 5 is a perspective view of a detached collecting 45 trough.

A machine in accordance with this invention comprises longitudinal side frames 1 connected by cross heads 2 and a flat plate 3, said flat plate having a central opening 4 formed therein. The side frames 1 are provided with depending supports 5 and 50 adjustably connected to said supports are legs 6 having longitudinal side frames 7, said legs and said side frames constituting a lower frame adapted to adjustably support the upper frame of the machine. The legs

6 are adjustably connected to the supports 5 by bolts 8 and winged thumb nuts 9, it being preferable to use a bolt at the upper end of said leg and a bolt directly beneath the frame 7 of said legs; the supports 5 being slotted, as at 10 to receive said bolts.

The outer sides of the supports 5 are provided with bearings 11 for transverse revolute shafts 12 and 13, said shafts being retained in engagement with said bearings by bearing pieces 14. The shafts 12 and 13, at one side of the machine, have beveled gear wheels 15 and 16 respectively, the beveled gear wheel 16 having the periphery thereof provided with teeth 17, whereby it will serve functionally as an ordinary gear wheel or pinion. Meshing with the beveled gear wheels 15 and 16 are small beveled gear wheels 18 mounted upon the ends of a longitudinal shaft 19, journaled in bearings 20, carried by the supports 5 adjacent to the bearings 11 upon one side of the machine. The bearings 20 extend outwardly, as best shown in Fig. 3, and it is through the medium of the shaft 19 carried by said bearings and the beveled gear wheels previously described that the shafts 12 and 13 are moved in unison in the same direction.

Meshing with the teeth 17 of the beveled gear wheel 16 is a large gear wheel 21 mounted upon a shaft 22, journaled in a bearing 23, carried by one of the supports 5. The large gear wheel 21 has an eccentric handle or crank 24, whereby the large gear wheel can be revolved with one hand, while the machine is moved with the other.

Mounted upon the shafts 12 and 13 are the hubs 25 of cylinders or drums 26 and 27. Mounted upon the drum 26 is a cover 28 having layers of felt or other absorbent material 29, said drum constituting a rotary absorbent roller that supports the rear end of the machine. The drum or cylinder 27 has the cover 30 provided with a brush or bristles 31, said drum and the bristles thereof constituting a rotary brush supporting the forward end of the machine.

Arranged within the opening 4 of the plate 3 is a receptacle 32 supported within the opening 4 by a plurality of radially disposed brackets 33 detachably connected to the plate 3 by bolts 34 and nuts 35. Riveted or otherwise connected to the bottom of the receptacle 32, as at 36 is a trough plate 37 having the ends thereof provided with perforated troughs 38. These troughs are lo-

cated above the sides of the rotary roller and brush and water is admitted to said troughs from the receptacle 32 through the medium of pipes 39 and faucets or spigots 40.

5 Secured to the inner sides of the frames 7 are the ends of a collecting basin or receptacle 41 and extending over the rear edge of said receptacle is a spout 42, carried by a collecting trough 43, said trough having the 10 ends thereof riveted or otherwise connected, as at 44 to the inner sides of the frames 7. The frames 7, at the ends of the trough 43 are provided with bearings 45 for a revol- 15 luble roller 46 adapted to engage the felt cover 29 of the absorbent roller and rinse water from the material.

The receptacle 32 can contain water or a liquid detergent mixture and by regulating the faucet or spigot 40 above the rotary 20 brush, a desired amount of liquid can drip on to the rotary brush. Two outlets are provided for the receptacle 32 in case it is desired to substitute a rotary brush for the absorbent roller, as might be done in a very 25 large building where a number of the machines equipped with rotary brushes can be used in connection with a number of machines equipped with absorbent rollers, one machine following the other, similar to the 30 absorbent roller following the rotary brush.

When the large gear wheel 21 is revolved with one hand, the machine is moved over the floor to be scrubbed and to facilitate its movement, the machine can be pushed with 35 the other hand, the two hands coöperating in quickly moving the scrubbing machine. As the rotary brush contacts with the floor, the bristles remove such dirt and foreign 40 matter that adheres thereto, and the dirty water left upon the floor by the brush is absorbed by the absorbent roller. The foreign

matter is removed from the absorbent material through the medium of the roller 46 and as the foreign matter enters the collecting trough 43, it is conveyed to the basin or 45 receptacle 41 by the spout 42.

It is through the medium of the adjustable frames of the machine that the upper frame can be lowered to compensate for the wear and tear upon the rotary brush and absorbent roller and to facilitate the movement of the machine over a floor, the lower ends of the legs 6 are provided with rollers or casters 47.

In order that the machine can be used 55 against or in proximity to the wainscoting of a wall, an auxiliary rotary brush 48 is mounted upon the end of the shaft opposite that end having the beveled gear wheel 16 and an auxiliary absorbent roller 49 is 60 mounted upon that end of the shaft 12 opposite the beveled gear wheel 15. In some instances these auxiliary devices can be dispensed with and the invention is not limited 65 to their use.

The machine can be made of light and durable metal and of various sizes.

What I claim is:—

A floor scrubbing and wiping machine comprising a rotary scrubbing roll, a rotary absorbent roll, a trough adjacent the surface of the absorbent roll, a wringer roll rotatable within the trough, a collection receptacle, and a conduit leading from the trough to the receptacle. 70

In testimony whereof I affix my signature in the presence of two witnesses.

MICHAEL VIDAK.
